(57) **CLAIM**

The ornamental design for a combined electromagnetic inductive potentiometer as shown and described.

DESCRIPTION

FIG. 1 is a front view of a combined electromagnetic inductive potentiometer, showing our new design in a combined state;

FIG. 2 is a rear view shown in FIG. 1;

FIG. 3 is a left side view shown in FIG. 1;

FIG. 4 is a right side view shown in FIG. 1;

FIG. 5 is a top plan view shown in FIG. 1;

FIG. 6 is a bottom plan view shown in FIG. 1;

FIG. 7 is a perspective view shown in FIG. 1;

FIG. 8 is another perspective view shown in FIG. 1;

FIG. 9 is a front view of a housing with electromagnetic inductive chip of the combined electromagnetic inductive potentiometer as shown in FIG. 1.

FIG. 10 is a rear view shown in FIG. 9;

FIG. 11 is a left side view shown in FIG. 9;

FIG. 12 is a right side view shown in FIG. 9;

FIG. 13 is a top plan view shown in FIG. 9;

FIG. 14 is a bottom plan view shown in FIG. 9;

FIG. 15 is a perspective view shown in FIG. 9;

FIG. 16 is another perspective view shown in FIG. 9;

FIG. 17 is a front view of a rotor with permanent magnet of the combined electromagnetic inductive potentiometer as shown in FIG. 1.

FIG. 18 is a rear view shown in FIG. 17;

FIG. 19 is a left side view shown in FIG. 17;

FIG. 20 is a right side view shown in FIG. 17;

FIG. 21 is a top plan view shown in FIG. 17;

FIG. 22 is a bottom plan view shown in FIG. 17;

FIG. 23 is a perspective view shown in FIG. 17; and,

FIG. 24 is another perspective view shown in FIG. 17.
